(57) **CLAIM**

The ornamental design for a belt exterior rear panel ornamentation, as shown and described.

DESCRIPTION

FIG. 1 is a perspective view thereof;

FIG. 2 is a rear elevational view thereof;

FIG. 3 is a top view thereof; and,

FIG. 4 is a side view thereof (the view from the other side is a mirror image).

The dashed broken lines in FIGS. 1-4 do not form a part of the claimed design.
